UNITED STATES PATENT OFFICE.

ASAHEL SOPER, OF WHITESTOWN, NEW YORK.

DESIGN FOR AN ORNAMENTAL CORNER-PIECE.

Specification forming part of Design No. 6,010, dated July 23, 1872.

Specification describing a Design for an Ornamental Corner-Piece, invented by ASAHEL SOPER, of Whitestown, in the county of Oneida and State of New York.

The nature of my design is fully represented in the accompanying photographic illustration, to which reference is made.

A represents the body of the corner-piece. B represents a pendant attached to and forming part of said corner-piece. C C represent the two sides of the aforesaid body, intended to

form joints with the square ends of moldings. D is the beveled face, and may be ornamented in any manner desired. Said corner-piece may be composed of wood or other material.

What I claim as my invention is—

The design for an ornamental corner-piece, substantially as shown and described.

ASAHEL SOPER.
